UNITED STATES PATENT OFFICE

99,171

DESIGN FOR AN ENVELOPE

Allan M. Thompson, Chicago, Ill., assignor to Gaw-O'Hara Envelope Company, Chicago, Ill.,
a corporation of Illinois

Application January 18, 1936, Serial No. 60,655

Term of patent 7 years

To all whom it may concern:

Be it known that I, Allan M. Thompson, a citizen of the United States, residing at Chicago, in the county of Cook and State of Illinois, have invented a new, original, and ornamental Design for Envelopes, of which the following is a specification, reference being had to the accompanying drawing, forming part thereof.

In the drawing:

The figure is a plan view of an envelope, showing my new design. The area enclosed by the circle is shaded to represent a transparent material forming a window in the wall of the envelope.

The envelope is of ordinary thickness.

I claim:

The ornamental design for an envelope, as shown and described.

ALLAN M. THOMPSON.
